Primary Examiner — Natasha Vujcic*Assistant Examiner* — Gilbert B Ford(74) *Attorney, Agent, or Firm* — Knobbe Martens Olson & Bear LLP(57) **CLAIM**

The ornamental design of a low-profile bedpan, as shown and described.

DESCRIPTION

FIG. 1 is a perspective view of a low-profile bedpan configured in accordance with the present invention;
 FIG. 2 is a top view of the low-profile bedpan;
 FIG. 3 is a bottom view of the low-profile bedpan;
 FIG. 4 is a left side view of the low-profile bedpan;
 FIG. 5 is a right side view of the low-profile bedpan;
 FIG. 6 is a back view of the low-profile bedpan; and,
 FIG. 7 is a front view of the low-profile bedpan.

The scope of the present disclosure encompasses all lines illustrated, whether broken or solid. Shade lines in the figures show contour or surface ornamentation.

1 Claim, 4 Drawing Sheets(56)
